UNITED STATES PATENT OFFICE.

JAMES W. MILLER, OF NEWARK, NEW JERSEY.

DESIGN FOR A SLEEVE-BUTTON OR SIMILAR ARTICLE.

SPECIFICATION forming part of Design No. 17,651, dated August 23, 1887.

Application filed June 2, 1887. Serial No. 240,099. Term of patent 14 years.

To all whom it may concern:

Be it known that I, JAMES W. MILLER, of Newark, in the county of Essex and State of New Jersey, have invented and produced a new and original Design for Sleeve-Buttons and like Articles, which design is fully set forth in the following specification.

This design is for the surface ornamentation of sleeve-buttons and other articles of jewelry, as well as analogous articles not generally classed as jewelry. It is illustrated in the accompanying drawings, in which—

Figure I shows the surface of a sleeve-button having the design formed thereon, and Fig. II shows in cross-section the elevations and depressions of the design.

My design consists in the ornamentation of the surface of jewelry with a series of figures or cells of irregular shape bounded by straight lines or ridges, producing a cellular or "cloisonné" effect, the same being placed upon the necessary lines of the letters. The cells or figures are made without regard to conformity or particular configuration, with triangular, quadrangular, or polygonal forms. The boundary-lines are preferably raised above or struck up from the surface of the article, though obviously the design is the same if the outlines be countersunk.

The letters shown on the drawings are the letter "S" and the letter "W" in old English,

being a modification of what is known as a "block letter;" but of course similar effects can be produced upon the other letters of the alphabet, as well as upon other kinds of letters. This ornamentation can be omitted from a part of the necessary lines of the letter without materially departing from my design. The outlines of the letters and of the figures covering the same are rendered more distinct and the effect of the design is enhanced when the surfaces adjacent to said lines present a color different from and affording a contrast to that of the lines themselves.

What I claim, and desire to secure by Letters Patent, is—

The design for the ornamentation of sleeve-buttons and other articles of jewelry and analogous articles, composed of a letter of the alphabet having an ornamentation upon the lines of the letter, consisting of rectilinear depressions or ridges constituting irregularly-disposed cells of triangular, quadrangular, or polygonal form, substantially as described and shown.

In testimony whereof I have signed this specification in the presence of two subscribing witnesses.

JAMES W. MILLER.
